SEWING MACHINE

Norman V. Christensen, Chicago, and George Sauer, Berwyn, Ill., assignors to Union Special Machine Company, Chicago, Ill., a corporation of Illinois

Application April 12, 1943, Serial No. 482,690

4 Claims. (Cl. 112—218)

This invention relates to improvements in construction and method of operation of a sewing machine, embodying a rotary loop-taking element, and associated devices. It has particular reference to provisions for increasing the efficiency and permissible speeds of operation of such machines.

A primary object of the invention has been to provide for the effective cooling or prevention of overheating of the stitch-forming devices of a machine of the character indicated and to prevent undue wear of such devices in the course of normal operation of the machine.

Another object has been to provide simple and inexpensive means for the purposes indicated, capable of producing the desired results without any appreciable addition to the cost of operation of the machine or the power required for such operation.

Heretofore, in the operation of machines having rotary hooks, several objectionable conditions have arisen to limit the permissible speed of operation of the machine and reduce its normal life. Thus, there has been a tendency in high speed operations to develop excessive heat in the needle or in the hook, or both. When the needle becomes overheated there is danger of thread scorching and breakage as well as deterioration of the needle itself. Overheating of the rotary hook renders the raceway lubricant less effective and leads to sticking, and hence greater friction and wear, between the rotating and non-rotating components of the hook.

In accordance with the present invention, these objectionable tendencies are eliminated or reduced to a minimum through the provision of a blast of cooling air directed continuously against the forward face of the hook, and around the latter, so long as the machine is in operation, a portion of such air reaching and serving to cool the operative end of the needle whenever the latter is below the work. The cooling air, so directed in a most effective manner, is derived, in accordance with the invention, from a blower driven by the motor which operates the sewing machine and the latter arrangement is such that no appreciable extra load is placed upon the motor.

Moreover, the blast of cooling air is of such character and so directed as to accomplish various additional beneficial results. It serves to remove from the rotary hook and the adjacent portions of the machine the small bits of lint which normally have a tendency to accumulate on these parts and induce wear as well as prevent

the dissipation of heat therefrom. So also, when the machine is operating upon fabrics loaded with various inert fillers, the air blast assists materially in preventing the fine filler particles from entering the hook raceway and combining with the lubricant to form, in effect, a lapping compound. In dealing with fabrics which are loaded particularly heavily with clay or the like, it is usually desirable to eliminate the lubrication of the hook raceway and at such times the cooling action of the blast of air and its tendency to clear away the particles of dust and lint are especially important.

Other objects, features and advantages of the invention will appear from the detailed description of an illustrative form of the same which will now be given in conjunction with the accompanying drawings, in which:

Fig. I is a view, partly in side elevation and partly in vertical section, of a sewing machine and its power driven means and associated devices, all shown as mounted upon a supporting table and constructed and arranged in accordance with the invention, only a portion of the table being illustrated.

Fig. II is an end view of the construction shown in Fig. I as viewed from the right.

Fig. III is an enlarged detail view showing, in bottom plan, a portion of the construction illustrated in Fig. I, parts of the sewing machine being illustrated in section.

Fig. IV is a face view of the rotary hook embodied in the illustrative machine and discloses the relationship between the hook and cooperating needle at a point in the cycle of operation of the machine, and

Figure V is an enlarged detail view showing in side elevation the relationship between the rotary hook, the needle, and the throat plate in the course of stitch formation, the throat plate being shown in section.

Referring now to the drawings, the invention has been shown as applied to a lock stitch sewing machine of the type disclosed in the patent to Christensen et al. No. 2,113,572, granted April 12, 1938. This machine comprises a base portion 10 providing a work supporting surface which is substantially flush with the surface of the top 11 of a supporting table. The base, as will be understood, is mounted in an opening or recess in the table top and may suitably be hingedly mounted on the latter or may simply be provided with a flange carried by the peripheral edge of the table opening. Rising vertically from one end of the base 10 is a vertical standard 12 car-

rying at its upper end a horizontally extending overhanging arm 13 provided at its free end with a needle head 14. A vertically reciprocable needle bar 15 is mounted in the needle head and carries at its lower end a needle 16 constituting a part of the stitch forming instrumentalities. A presser foot 17 of suitable construction is mounted at the lower end of a presser bar 17a, which is also slidably mounted in the needle head and is urged yieldingly downward by an appropriate spring (not shown). For the purpose of operating the needle bar, there is provided within the arm 13 a longitudinally extending shaft 18, the end of which projects beyond the vertical standard 12, as shown in Fig. I. To this shaft 18, may be secured the conventional hand wheel and pulley 18a through which power is supplied to the various operating devices of the machine.

As disclosed in said Christensen et al. patent above mentioned, suitable gearing may be provided between the shaft 18 and a shaft 19 (Fig. III) which extends longitudinally of the base 10. Shaft 19 carries suitable eccentric means cooperating with an eccentric strap 20 and an arm 21 appropriately connected with the work feeding devices of the machine for imparting the feed movement and the lifting and lowering movements to the feed dog. The latter, which is not shown, may be suitably mounted upon a feed bar 22, which is given the desired movements by the eccentric means mentioned above, in the manner more fully set forth in said Christensen et al. patent. At an intermediate point there is secured to the shaft 19 a gear 23 which meshes with a pinion 24 secured to a hook shaft 25 mounted in a long bearing sleeve 26 carried by the frame of the machine base. The gearing 23 and 24, which is enclosed in an oil-tight housing, as illustrated in Fig. I, is such as to impart two revolutions to the shaft 25 for each revolution of the shaft 19 and for each reciprocation of the needle bar 15. At its forward end the shaft 25 carries a rotary component 27 of a conventional two-to-one rotary hook. Within the rotary component there is mounted a stationary component 28 constituting a bobbin holder, this being held against rotation by a detent 29 (Fig. III) secured to the under side of the work support. As will be understood, the hook illustrated is of the raceway type, in which a suitable rib provided on the stationary component cooperates with a groove or raceway in the rotary component. Any suitable means may be employed for lubricating the raceway. For this purpose there is partially illustrated in Fig. III a lubricant reservoir 30 mounted beneath the work support and having one end fitted over the end of a bearing sleeve 31 in which the end of the hook shaft 25 is journaled. This construction may be of the type illustrated in the application of John G. Attwood, Ser. No. 473,804, filed on January 28, 1943. As disclosed in said application, the construction may be such that oil may be fed from the reservoir 30 through a longitudinally extending bore within the shaft 25 to the rotating component of the hook, which upon revolution will cause the oil to be delivered to the raceway.

For the purpose of driving the sewing machine, there may be provided beneath the supporting table 11 an electric motor 32 having associated therewith a power transmitting clutch housing 33. This transmitter unit may suitably be of the type disclosed in the Patent No. 2,037,844, granted to Max T. Voight on April 14, 1936, and it may be mounted on the under side of the table top in the

manner disclosed in the pending application of George Sauer, Ser. No. 442,585, filed on May 12, 1942. The mounting may include a plate 34 secured to the top of the housing 33 and having a downwardly extending arm 35 (Fig. II), which is connected by a pivot (not shown) with a downwardly extending arm 36 integral with a plate 37 secured to the under surface of the table top. A bolt 38 pivoted upon the plate 37 and cooperating with a forked extension of the plate 34 may serve to retain the motor and clutch unit at a desired elevation to provide proper tension on the driving belt, to be hereinafter described.

The shaft 39 of the motor extends into the clutch housing 33 and carries adjacent its end a flywheel 40 forming the driving element of the clutch. Axially aligned with the shaft 39 is a driven shaft 41 carrying a driven element 42 of the clutch. Shaft 41 is mounted in suitable bearings within a sleeve 43 carried by an extension 44 of the housing. The arrangement is such that the sleeve 43 may be shifted axially to a limited extent within the support 44. For this purpose pins or projections 45 carried by the sleeve 43 may extend through elongated openings in the portion 44 of the housing and may be engaged by the forked, upper ends of a bifurcated portion of an operating lever 46 pivoted at 46a upon the clutch housing. A spring 47 normally urges the lever 46 in a clockwise direction (Fig. I) to shift the sleeve 43 toward the right and disengage the clutch. The lever 46, however, may be rocked in a counter-clockwise direction in any suitable way, as by means of a link 48 connected with a foot treadle, or the like, to bring about engagement of the clutch at will.

Secured to the shaft 41, which is shifted in the manner explained, is a pulley 49 connected by a belt 50 with the pulley 18a secured to the main drive shaft 18 of the sewing machine. Power is thus transmitted to the sewing machine from the motor 32 whenever the clutch is engaged by the axial shifting of the shaft 41 and clutch member 42. A supporting plate or frame 51, preferably of C-shape, as shown in Fig. II, is adjustably mounted on the clutch housing by a plurality of bolts 52. As set forth more fully in the pending Sauer application, above mentioned, this construction is such as to permit both angular and axial adjustment of the plate 51 with respect to the axis of the shafts 39 and 41. A blower housing 53, preferably of the construction set forth in said Sauer application, is detachably connected with the frame 51 by means of wing-headed screws 54. Spacing collars 55 serve to retain the housing in properly spaced relation to the plate 51. A belt guard 56 may suitably be attached by screws or the like to the spacing collars 55. Within the blower housing is provided an impeller 57 which is secured by screws 58 to the hub of the pulley 49. This impeller, as will be understood, is shifted axially to a limited extent as the shaft 41 is shifted in the engagement and disengagement of the clutch. The adjustment of the plate 51, in the manner above indicated, allows for the relative shifting of the impeller and blower housing to eliminate interference between these parts, both in the original assembly of the parts and by way of compensation for wear.

The blower housing has an outlet member 59 which is connected, preferably, by a flexible coupling 60, formed of rubber or a suitable synthetic composition, with the lower end of a tubular conduit 61. The latter, which may suitably be formed of metal or an appropriate plastic or may simply

be a flexible hose, preferably, has an internal diameter of about $\frac{3}{4}$ of an inch and is shaped or bent, as indicated in Figs. I and II, to extend horizontally along the rear edge of the table top, or, if desired, it may be positioned beneath the table top or within a groove in the under surface thereof. It may suitably be supported adjacent the blower outlet by means of a bracket 62 (Fig. II) secured to the under side of the table and it may be supported at an intermediate point by a loop or bracket 63 (Fig. III) secured to the under side of the table along its rearward edge. Beyond the bracket 63 the tube or conduit is bent through a sweepingly curved portion 64 in such a way as to point its free end in the opposite direction. Another loop or bracket 65 may be employed to hold a portion of the tube, adjacent its free end, against the under surface of the table. The discharge end 66 of the conduit has an outlet of the same diameter as the conduit as a whole and is so positioned as to direct the stream of air generated by the blower against the outer face of the rotary hook. Preferably, as shown, the discharge end of the conduit is directed upwardly and inwardly at a slight angle. The appropriate inclination to the horizontal may be established by cutting away the under surface of the table along the edges at one corner of the opening through which the base of the sewing machine extends, as indicated at 67 (Figs. I and III) and providing a sloping under-surface 68 (Fig. I) at the desired angle on the portion of the table engaged by the discharge end of the conduit just in advance of the cut away portion. The spacing of the outlet 66 from the face of the rotary hook is preferably about 2 or 3 inches which is just sufficient to provide ready access to the hook and permit the removal of the bobbin holder 28 from the rotary component 27 without disturbing the relative positioning of the parts. This is facilitated, furthermore, by the location of the outlet 66 at one side of the axis of the hook shaft, as shown in Fig. III. The arrangement is preferably such that the sewing machine as a whole may be swung backwardly on its hinges or lifted from the opening in the table, to permit access to the base of the machine, without disturbing the conduit. Due to the spacing indicated, between the outlet 66 and the face of the hook, the stream of air discharged from the conduit is permitted to expand in the manner shown by the arrows in Figs. I and III and, thus, complete envelopment of the rotary hook is insured. A number of desirable effects are accordingly produced. Firstly, the temperature of the hook is kept within desirable limits; secondly, the accumulation of lint and filler material on and within the hook is prevented; thirdly, the needle is subjected to a desirable cooling action whenever the point is carried below the work, and fourthly, lint and filler are blown away from the openings 69a and 69b (Figures IV and V) in the throat plate 68 through which the needle and feed dog operate. This latter function is assisted by the upward inclination of the discharge end of the conduit. A still further desirable effect of the blast of cooling air directed in the particular manner contemplated by the present invention is that it serves to assist in opening up the needle thread loop for the proper reception of the loop-seizing beak of the rotary hook. This is illustrated in Figure V. The needle in this figure is illustrated in the position it assumes immediately after it commences its upward movement. This upward movement tends to form a loop 70 in the needle thread. Im-

mediately thereafter the thread-seizing point, or beak 71 of the hook enters the loop and thus causes the needle thread to be cast around the bobbin case. The air blown in the direction contemplated by the present invention serves to open up the loop 70 by blowing this toward the right in Figure V away from the needle. Thus proper cooperation between the hook point 71 and the loop 70 is insured. If the blast of air were blown in the opposite direction it would be seen from Figure V that it would tend to close the loop 70 and thus interfere with the proper cooperation of the hook point 71 with the loop. The same may be said with respect to a blast of air directed upwardly from beneath the hook, since this passing around and through the openings in the hook will have a tendency to cause the loop 70 to flatten out against the needle.

It has been found desirable to discharge the continuous stream of cooling air at a velocity of between 10 and 100 ft. per second and preferably between 50 and 70 ft. per second. In the use of a conduit of the character indicated an adequate amount of air, say between .1 and .3 of a cubic foot per second, may be delivered to the hook with a pressure in the conduit of only about 1.3 inches of water above atmospheric. Discharge, in the manner indicated, of the relatively low velocity and low pressure air through a space of rather large cross-sectional area has been found to impart a substantial cooling effect to the hook and to bring about a quite substantial reduction in the temperature of the needle. It may be noted, in this connection, that the needle is in a position in which its point is accessible to the cooling air, as shown in Fig. IV, for a substantial portion, i. e., fully one-quarter, of each cycle of the machine. The elimination of lint on and around the rotary hook and from the passages in the throat plate by virtue of the continuously moving stream of cooling air, is an important factor in preventing over-heating of the hook, since the most serious overheating has resulted from the insulating effect of a coating of lint and dust which has a tendency to accumulate on the hook.

While a preferred form of apparatus embodying the invention and a preferred mode of operation have been explained in detail in the foregoing it will be understood that numerous variations may be employed in the specific construction and arrangement of the parts and in the mode of attaining the purposes of the invention without departing from the general principles and scope of the invention. The terms and expressions used herein have been used as terms of description and not of limitation.

We claim:

1. A machine of the class described comprising a work supporting member, needle carrying and operating mechanism arranged to carry a needle to and through work on said supporting member, a rotary hook having a bobbin holder beneath said member cooperating with said needle in stitch formation, means associated directly with said machine and including an electric motor and connections therefrom for driving said needle operating mechanism and said rotary hook, a blower associated with said electric motor and driven thereby for creating a low pressure, low velocity stream of air, and a conduit from said blower to a point adjacent said rotary hook for delivering said stream of cooling air and directing the same substantially normal to and against the forward face of said hook and around the sides thereof, the discharge end of said con-

duit being fixed at only a sufficient distance from said hook to enable ready access thereto for the removal of said bobbin holder.

2. A machine of the class described comprising a work supporting member, needle carrying and operating mechanism arranged to carry a needle to and through work on said supporting member, a rotary hook beneath said member cooperating with said needle in stitch formation, a power unit associated directly with said machine and including an electric motor and a clutch, connections from said unit to said machine for driving said needle operating mechanism and said rotary hook, a blower mounted on said power unit and arranged to be driven thereby to create a low pressure stream of cooling air at a velocity between 10 and 100 feet per second, and a conduit from said blower to a point adjacent said rotary hook for delivering said stream of cooling air and directing the same substantially normal to and against the forward face of said hook, the discharge end of said conduit being fixed and spaced from said hook only a sufficient distance to provide ready access to said hook, the conduit being of substantially uniform cross-sectional area throughout and capable of conducting between .1 and .3 of a cubic foot of air per second at a velocity of not more than 100 feet per second, said conduit being arranged to discharge the air at such velocity toward and around the hook.

3. A machine of the class described comprising a work supporting member having a throat plate, needle carrying and operating mechanism arranged to carry a needle to and through work on said supporting member and then through said throat plate, a rotary hook beneath said member cooperating with said needle in stitch formation, a power unit associated directly with said machine and including an electric motor and a clutch, connections from said unit to said machine for driving said needle operating mechanism and said rotary hook, a blower mounted

on said power unit and arranged to be driven thereby to create a low pressure stream of cooling air at a velocity between 10 and 100 feet per second and a conduit from said blower to a point adjacent said rotary hook for delivering said stream of cooling air and directing the same against the forward face of said hook, the discharge end of said conduit being fixed and spaced from said hook only a sufficient distance to provide ready access to said hook, and being directed substantially axially of said hook but upwardly at a small angle toward the under side of the throat plate, thereby creating a slight outward pressure through said throat plate.

5 15 4. In apparatus of the class described a supporting table, an opening through the top thereof, a sewing machine supported by said table top and having a base portion adapted to extend through said opening, said machine having a throat plate and stitch forming devices including a needle arranged to pass through said plate and a horizontal axis rotary hook exposed beneath said table top, a motor and clutch unit carried by said table beneath said top, driving connections from said unit to said sewing machine for operating the latter, a blower carried by said unit and driven thereby to create a low pressure and low velocity stream of cooling air, a conduit connected with said blower extending beneath said table top to a point in front of said hook, the discharge end of said conduit being fixed and directed upwardly at a small angle not exceeding 30° to the horizontal substantially in the plane of the axis of said hook and arranged to direct 20 25 30 35 40 said stream of cooling air toward and against the forward face of said hook and around the same and indirectly through said throat plate, said hook being sufficiently open at its forward face to provide access of said cooling air to the needle at times.

NORMAN V. CHRISTENSEN.
GEORGE SAUER.
